Jack Richmond

Attorney

UNITED STATES PATENT OFFICE.

WILLIAM L. HOFFMAN, OF EASTON, PENNSYLVANIA.

POWER-OPERATED SCISSORS.

Application filed April 1, 1925. Serial No. 19,872.

To all whom it may concern:

Be it known that I, WILLIAM L. HOFFMAN, a citizen of the United States, residing at Easton, in the county of Northampton and State of Pennsylvania, have invented certain new and useful Improvements in Power-Operated Scissors, of which the following is a specification.

My invention relates to mechanically or automatically operated cutting implements and more particularly to shears or scissors.

While clippers and the like cutting implements have gone into more or less extensive use, no serious attempt has been made to market motorized shears or scissors for the reason that such as were proposed did not have the essential or desirable relative vibratory movement of the blades as obtained with manually operated implements.

The object of my invention is to provide for such essential or desirable movement, and, at all events, to provide an implement of the nature indicated that shall be comparatively simple in construction, inexpensive and highly efficient when applied to any use to which ordinary hand shears or scissors are adapted.

The invention in its preferred form is illustrated in the accompanying drawing wherein—

Figure 1 is an elevational view with one of the handle complements removed to disclose the operating mechanism,

Figure 2 is an edge view,

Figure 3 is a section on line 3—3 of Figure 1, and

Figure 4 is a perspective view of the operating mechanism detached.

According to my invention a pair of cutting blades 5 of the usual scissors type is pivoted for relative opening and closing movement. The pivot may be a bolt or stud 6 constituting one of the connecting elements of a pair of hand grasping or handle complements 7 and 8, which constitute a casing or housing for the rearwardly extending arms 9 of the blades and for the instrumentalities for vibrating the same. In the present embodiment the cutting blades are actually mounted in the complement 7 which is shaped or cored as at 10 for that purpose, the other complement really being a cover plate and also operating to provide the ad-

ditional thickness, as at 11, to enable the handle to properly fit the closed palm of the operator.

A driven shaft 12 ranging transversely the handle or casing is journaled at one end in the side wall of the member 7 and at the other end in a partition 13 which takes a flush fit in edge recesses 14 of said member. The shaft 12 accommodates a vibrating element or cam block 15 mounted between the blade arms or jaws 9 and serving to part them against the closing effort of a retractile or coiled spring 16 engaging the terminals of the jaws. Shaft 12 also accommodates a worm pinion 17 through which it derives its motion.

A driving shaft 18 ranging longitudinally of the handle portion is journaled in a pair of lug extensions 19 of the partition 13. It is formed or provided with a worm 20 which meshes with the pinion 17. The other or free end of the shaft is accommodated in the sleeved portion 21 of the handle and has a split tubular externally threaded portion 22 for engagement with the usual flexible shaft, not shown. The handle has an externally threaded neck portion 23 to receive a thimble or coupling which may be an adjunct of the flexible shaft. It has been found in practice that the constant speed transmitted to the cam through the agency of the worm drive is the nearest approximation to manual operation.

Having described my invention, I claim:

A motorized cutting implement comprising a twopart casing externally shaped to fit within the closed hand, a partition seated in one part of such casing and held in position by the other part of the casing, pivotally connected blades mounted at one end of the casing and extending beyond the same as cutting portions and within the same below the partition as operating members, a rotating element supported in the partition and formed to actuate the operating members, and a shaft mounted in the upper portion of the casing and supported on the partition, said shaft operating said rotating element.

In testimony whereof I affix my signature.

WILLIAM L. HOFFMAN.
